UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

TRAIN CONTROL.

Application filed April 28, 1924. Serial No. 709,470.

This invention relates to automatic train control systems of the continuous inductive type, and more particularly to the provision of means for governing train movements over 5 portions of the track which are not equipped for automatic train control.

In equipping a railway system with automatic train control it is often found necessary, either because only part of the main railroad 10 can be equipped for train control or because of branches, sidings, yards, cross-overs leading to tracks equipped only for oppositely directed traffic and the like, to leave certain portions of the railroad unequipped as far as 15 train control apparatus is concerned. Such portions of the road may or may not be equipped with the usual way-side signals depending on the character of such portion and the importance of the traffic moving there- 20 over. Such unequipped or non-train control territory is preferably referred to as non-signal territory hereinafter.

In train control systems of the continuous inductive type in which the freedom of move- 25 ment of the train depends on the presence of current flowing in suitable trackway circuits adjacent the train it is important to provide some means to make the car-carried equipment of the train control apparatus in- 30 effective when a train enters into non-train-control, non-equipped or non-signal territory, because if such provisions were not made the train would be unnecessarily restricted in such territory, the automatic control being 35 preferably automatically reinstated when signalled territory is re-entered.

In an automatic train control system including cab-signals for indicating traffic conditions ahead it is important that such cab- 40 signals tell the truth, and if non-signal territory is entered the engineer should be informed of this fact and he should be continually reminded that he is running in such territory until he re-enters signalled territory. This is necessary so that the engineer 45 may take special precaution since the safety of the train depends entirely on him while he is moving in such territory.

In certain types of systems it is only found 50 necessary or expedient to use two of the three positions available in a relay of the three-position type, and the present invention is more particularly directed to a train control system in which a three-position relay is 55 used, and in which the third position has

been utilized to set up a non-signal territory control and cab-signal indication. The three-position relay referred to assumes an extreme position in one direction or the other depending on the character of the current or 60 currents applied thereto and assumes a de-energized position by reason of a spring or gravity acting to bias it to such position when deenergized.

More specifically the objects and purposes 65 of the present invention consist in the provision of a suitable stick relay, for instance, which is placed in its active condition when the three-position relay heretofore referred to assumes the third position, and the pro- 70 vision of means to maintain such device stuck up or active so long as the three-position relay assumes its biased or deenergized position, the provision of suitable cab-signalling means 75 for manifesting whether or not the train is moving in train control or signal territory, and the provision of suitable speed control apparatus.

Other objects, purposes and characteristic 80 features of the invention will appear as the description thereof progresses.

In describing the invention in detail reference will be had to the accompanying drawings in which:

Fig. 1 shows in a conventional manner car- 85 carried apparatus embodying the present invention, and trackway apparatus and circuits for both way-side signalling and train control purposes, and

Fig. 2 shows a continuation of the track 90 and equipment therefor shown in Fig. 1 and a portion of trackway of non-signal territory which is not equipped for train control purposes.

In disclosing the present invention an illus- 95 trative form of a train control system of the three-position continuous inductive type has been shown in which the various component parts, such as the three-position relay, the amplifying devices and influence receiving elements, may be the same as corresponding parts of the apparatus shown in the patent to Lewis No. 1,351,771 dated September 7, 1920, in combination with which the novel non-signal territory control and signal apparatus has been shown. In view of this fact it is considered sufficient to give a brief description or survey only of the system itself. It should be understood that the invention 100 is not limited to the specific form of system 110

shown, but that it is applicable to any other form of system having similar functions and mode of operation, and although the system has been applied to a signal system employing alternating current track circuit control it may be applied to systems using direct current for this purpose.

Trackway apparatus.

- 10 *Train-control territory.*—Referring to Fig. 1 of the drawings there has been shown a track divided into blocks by insulating joints 1, the block I and the adjacent ends of two other blocks H and J being shown. This 15 track comprises sections of territory which are equipped with train control apparatus as well as sections which are not so equipped. Although the train control system embodying the present invention may be applied 20 to trackway equipment which does not include wayside signals, or to systems provided with color light, position light or semaphore signals, it has been shown applied to a system in which semaphore signals Z are used, 25 which have been shown conventionally without illustrating their well-known control circuits and devices. Since the various elements of the various blocks are the same, like reference characters having distinctive 30 exponents are assigned to the various parts of the various blocks. The block I is provided with a suitable track relay T which derives its energizing current from the usual track circuit, which, in the arrangement 35 shown, includes a source of alternating current as indicated by the transformer 2 the secondary winding of which is connected across the rails at the exit end of this block through an impedance 3.
- 40 The usual track circuit, which hereinafter is conveniently referred to as a loop circuit or track phase, is also used for transmitting control influences to the moving train. In addition to this track circuit there is also 45 provided a circuit which comprises the two track rails in multiple and which is for convenience called a simplex circuit or line phase. In the particular arrangement shown the block I is divided into two sections by the 50 balancing resistance 6, each having a separate simplex or line circuit. The first section of this block has its line phase energized by a transformer 7, and includes the secondary winding of this transformer. This line 55 phase or circuit may be traced from the secondary winding of this transformer 7, wire 8, middle point of balancing resistance 6 through the two rails in multiple to the middle point of balancing resistance 9, from 60 whence it returns through wire 10 back to the secondary winding of this transformer 7.
- Under clear traffic conditions of the block J the second section of the block I is energized by a similar but controllable line circuit which may be traced as follows:—begin-

ning at the secondary winding of the transformer 13¹ wire 14¹, front contact 15¹ of the track relay T¹, wire 16 to the middle point of balancing resistance 17, the two track rails in multiple, to the balancing resistance 70 6, and from the middle point of this balancing resistance through wire 18, back to the other terminal of this transformer 13¹. It is therefore noted that if the block I is a caution 75 block because the block J in advance is occupied by a train, that the first section of the block I will have line circuit current flowing therein whereas the second section of this block has its line circuit broken at the front contact of the track relay T¹. The absence 80 of line circuit current in this second section will control the train as more clearly described in the operation of the system hereinafter.

Non-signal territory.—Referring to Fig. 2 of the drawings there has been shown a continuation of the track-way shown in Fig. 1. The end of the block J is the exit end of signalled territory. At the entrance to non-signalled territory is found a short section of 90 trackway which has track circuit current as well as line circuit current applied thereto, these currents, however, having a phase relation reverse to that between similar line and track currents in signalled territory. In the particular arrangement shown the track circuit current at the entrance to unoccupied territory is supplied by a transformer 20 through an impedance 21 which current is also used for energizing the track relay T² when this short section is unoccupied. The line circuit current for this section is supplied by a transformer 22 and flows through a circuit which may be traced as follows:—beginning at the secondary winding of this 95 transformer 22, wire 23 to the middle point of balancing resistance 24, through the two rails in multiple to the middle point of balancing resistance 25 through wire 26 back to the secondary winding of this transformer. To properly control a train in the block J the line circuit of the second section of the block J includes the front contacts of the track relays T² and T³ and the wire 14^a in addition 100 to the circuit portions of the corresponding circuit in the block I.

Car-carried apparatus.

In the block H has been shown a railway vehicle conventionally illustrated by the axles and wheels 30 and 31. In order to illustrate, in a simplified manner, one embodiment of the present invention this railway vehicle has been shown equipped with track circuit current receiving elements LE in front of the first axle each of which elements includes a coil 34. These two coils 34 are connected in series in a manner so that alternating current voltages induced therein by reason of track circuit current flowing in opposite direc- 115 120 125 130

tions in the two track rails are cumulative, and are connected to the input side of an amplifying device LA, which has been conventionally shown as a square and in practice includes a suitable thermionic amplifier of the vacuum tube type and associated apparatus which is adapted to receive and amplify the currents induced in these track circuit receiving elements LE. Although these receiving elements have been shown as including cores, such cores may be omitted if desired. The exit or output side of this amplifying device LA is connected to a winding 35 of a three-position alternating current main relay MR.

From a suitable point in the rear of the first axle in the train and preferably in the rear of the tender is hung another pair of influence receiving elements similar to those already described, which are connected so that the voltages induced in their coils by reason of currents flowing in the same direction in both rails are cumulative. These influence receiving elements have been designated SE and are connected to the input side of the amplifying device SA, similar to the one already described, the output side of which is connected to the other winding 36 of the main relay MR. This main control relay 30 MR is provided with contacts 37 and 38 which have been conventionally shown and which assume an intermediate position to which they are biased if either or both of the windings 35 or 36 are deenergized, assume the left hand or normal position when the two windings 35 and 36 are energized by currents derived from track and line phases in signalled territory, and assume the reversed or dotted position when these windings are energized 40 by current in the track and line circuits when moving over the short section at the entrance to non-signal territory. This distinctive positioning of the relay at the entrance to non-signal territory is due to the distinctive phase 45 relation of the track and line phases in this short section.

The train control system embodying the present invention preferably includes a suitable brake applying device for applying the brakes automatically under certain conditions. Although this brake applying device may be one which actuates the usual engineer's brake valve, or may be a suitable application valve which vents the brake pipe to a predetermined extent only when actuated, an electro-pneumatic valve EPV for controlling such brake control device has been shown conventionally, it being understood that the present invention is not limited to any particular form of device for controlling the brakes.

In order to gradually restrict the limiting speed of a train in a caution block and to enforce a low limiting speed in an occupied block a suitable speed restricting device is preferably employed, which restricts the

speed thereof in accordance with the progress of the train along the track, such for instance, as shown in the patent to Simmen #1,150,309 dated August 17, 1915, and for convenience a simple speed restricting device of this kind 70 has been shown conventionally and will only be briefly described. The particular speed restricting apparatus shown includes a cam which is normally held in a maximum speed position and which is gradually rotated to 75 set up lower speed limits when initiated in accordance with the progress of the train through the block. A suitable speed indicator is preferably employed to indicate the speed at which the train is traveling at any time, 80 and a speed responsive device or governor S of the centrifugal type has for convenience been shown for this purpose.

This speed responsive device S is located on the shaft 40, driven from the wheels of the vehicle in any suitable manner, and includes a collar 41 pinned to this shaft and another grooved collar 42 which is slidably mounted on this shaft having links 43 pivotally secured thereto which are pivotally connected 90 together by centrifugal weights or fly balls 44, these collars normally being urged apart by a compression coil spring 45.

Suitably mounted with respect to the governor S is a speed shaft 47, on which is pinned 95 a bifurcated arm 46 having pins in the bifurcated end thereof engaging the groove in the collar 42, so that the shaft 47 turns in response to the change of speed of the vehicle. To this shaft 47 is also fastened a speed arm 100 48, which has its free end pivotally connected to a floating lever 49, the other end of this lever being provided with a roller 50 engaging the cam surface of the cam 51 more clearly described hereinafter. Pivotally secured 105 to an intermediate point on this floating lever 49 is a link 52, which has its other end connected to an eccentrically located pin 53 on a contact operating sector 54. This sector is biased in a counter-clockwise direction by the 110 spring 55, whereby a tension is produced in the link 52 to maintain the roller 50 of the floating lever in engagement with the cam 51. The sector 54 has an arcuate cam surface, a portion of which, as shown, is cut down so 115 that as this sector is rotated in a clockwise direction a certain distance, the roller 56 rolls into the cut-away portion and thereby causes contacts 57 and 58 to open for purposes more clearly described hereinafter.

The cam 51 heretofore mentioned is pinned to the cam shaft 60, the other end of which is fastened to a mutilated gear 61. The mutilated gear 61 is adapted to be driven in one direction or the other, depending on the direction in which the vehicle is moving, by a train of gears suitably driven from the axles of the railway vehicle. In the particular arrangement shown, a worm 63 is provided on the shaft 40 which engages a worm wheel 64 hav-

ing a pinion 65 associated therewith which engages the gear 66. Pivotaly supported with respect to the shaft on which the gear 66 is mounted to rotate is a control arm 67 having a portion thereof bifurcated, with the bifurcated portion straddling the gear 66 which arm is biased upward by a spring 68 surrounding the guide pin 69. In the bifurcated portion of the control arm 67 is pivotally secured a pinion 70 in meshed relation with the gear 66. To the control arm 67 is fastened an armature 72 which is adapted to be attracted by a cam starter magnet CS energized under clear traffic conditions. It is thus noted that deenergization of the cam starter magnet CS causes engagement of the pinion 70 from the mutilated gear 61 thereby causing rotation of the cam shaft 60 and cam 51 in response to the progress of the train.

After a predetermined distance of travel of the train after this cam starter magnet CS has been deenergized, which may be assumed to be the braking distance of the train in question, the gear 61 will have been rotated substantially 180°, after which the pinion 70 is free to rotate without further rotation of the gear 61 by reason of the provision of the mutilated portion of this gear 61. In order to again return the cam 51 to its normal position, as shown, when the cam starter magnet CS is again energized a suitable spring pressed gear sector is provided. This gear sector 75 is pivotally supported about the journal 76 and is in meshed relation with a pinion 77 secured to the cam shaft 60. This sector 75 is biased to its intermediate position by two opposing springs 78 contained between the leg of this sector and stationary lugs or stops 79.

40 Operation.

Entering signal territory.—Under normal clear traffic conditions of the car-carried apparatus the main control relay MR is energized to assume the left hand or clear position, under which condition an emergency circuit for the cam starter magnet CS is closed as follows: beginning at the terminal B, of source of energy, wire 88, contact 37 of the main relay MR, wires 89 and 90, winding of the cam starter magnet CS, wire 91, back to common return wire C. If the speed of the train is not excessive an energizing circuit for the brake control device EPV as follows is intact:—beginning at the terminal B, wire 92, contacts 57 and 58, controlled by the sector 54, wires 93 and 94, winding of the device EPV, wire 95 back to the common return wire C. With the train moving with the cam 51 in its restored position a certain maximum speed limit is set up by reason of the speed responsive device S controlling contacts 57—58 through parts 46, 47, 48, 49, 52 and 54. It should be noted that a green or clear signal lamp G is energized under normal clear traffic

70 traffic conditions of relay MR and that a danger or red lamp R is energized when this relay assumes a deenergized position and the relay NS is also deenergized, by circuits readily traced in the drawings.

If, now, the cam starter magnet is deenergized for any reason, probably because the train has passed the balancing resistance 6 in a caution block and no longer is capable of receiving line current, or possibly because track circuit current is shunted away by another train ahead, a variable restrictive speed limit is caused to be set up by contacts 57—58, which speed limit is gradually lowered as the train progresses, by reason of the turning of cam 51. If this speed limit is exceeded these contacts separate and interrupt the energizing circuit for the device EPV, thereby affecting a brake application. The cam 51 is preferably so geared with respect to the wheels of the train that if the cam movement is initiated as a result of movement of the train into a caution block the mutilated portion of the gear reaches the pinion 70 when the train reaches the exit end of the block, and when the cam reaches this ultimate position a continuing minimum speed limit is imposed.

95 As the train moves into the following block, which of course must be an occupied block if the preceding block was a caution block, this causes the cam to continue to assume the ultimate position, for, although there may be line current present in this occupied block no track circuit current is flowing because it is shunted away by the train ahead, it of course being understood that if the block in question is a danger block for some other reason such as an open switch, or the like, this fact will be manifested by the absence of either the line or track phase current altogether. It should be noted that the line phase circuit is cut off beyond the balancing resistance 6 only, in a caution block. This is done so that the train may proceed as in a clear block until it is substantially braking distance from the entrance to a danger block.

110 *Entering non-signalled territory.*—Let us assume that the train proceeds through the block J under clear traffic conditions ahead and that it reaches the entrance end of the block K which is also the entrance to non-signalled territory. It should be borne in mind that the engineer should be properly informed when he enters non-signalled territory so that he may know that the safety of the train depends entirely upon him because no automatic control is provided for in such territory. As the train enters this short section (resistance 25 to resistance 24), provided with a line circuit having a current flowing therein which has a reverse phase relation to the track circuit current of this portion from that of the relation of the line and track circuit currents in signalled territory,

- the main control relay MR is energized in the reverse direction, thereby causing a pick up circuit for the non-signal territory relay NS to be closed, which may be traced as follows:—beginning at the terminal B of said source of energy, wire 88, contact 37 of the main control relay MR in its reverse position, wires 100 and 101, winding of the relay NS, wire 102, back to common return wire C. 5
- With this pick up circuit completed this relay assumes its energized position and closes all of its front contacts, and as soon as the train passes out of this short section the main relay MR assumes its deenergized position, 10
- because no line phase current is present, although track circuit current may or may not be present, depending on whether or not track circuit current of the same character is used for block signalling purposes in unsignalled 15
- territory, thereby closing a stick circuit for this NS relay which may be traced as follows:—beginning at the terminal B, wire 88, contact 37 of the main relay MR, in its biased or deenergized position, wire 103, 20
- front contact 104 of the NS relay, wires 105, and 101, winding of the NS relay, wire 102, back to common return wire C. It is of course understood that the relay NS is sufficiently slow acting to maintain its front contact 104 25
- closed while the relay MR changes from its reversed position to its deenergized position. This relay NS is thus closed in an energized stick circuit which is completed so long as the main relay MR is deenergized. With the 30
- relay NS energized the non-signal territory or white lamp W is illuminated through a circuit including the front contact 83 of this relay in its raised position which is readily traced in the drawings. 35
- With the NS relay energized the cam starter magnet CS is maintained energized through the following circuit:—beginning at the terminal B, wire 106, front contact 107 of the relay NS, wires 108 and 90, winding 40
- of the cam starter magnet CS, wire 91 back to return wire C. Also, a circuit for the brake control device EPV is completed under this, the non-signal territory traffic conditions which may be traced as follows:—beginning 45
- at the terminal B, wire 110, front contact 111, of the NS relay, wires 112 and 94, winding of the EPV, wire 95 back to return wire C. Since the device EPV is held up by the front contact 111 while the train is moving in non-signal territory it would seem unnecessary 50
- to hold the cam 51 in its restored position by energizing the cam starter magnet CS. This magnet CS is however maintained energized in non-signal territory so that no unnecessary 55
- wear on the gear 61 and pinion 70 will take place by turning of this pinion in the mutilated portion of this gear. 60
- As long as the train is moving in non-signal territory the speed of the train is unrestricted in the particular arrangement shown, 65
- but if desired a special continuing predetermined speed restriction may be set up by this relay NS. If no special speed restriction in unsignalled territory is provided for, the usual safety afforded when no train control apparatus is employed, that is, that afforded by the engineer, is present here, because the engineer is continually advised that the safety of the train depends entirely upon him by reason of the provision of the non-signal territory signal W which may be a signal of any desired type either visual or audible, but has for convenience been shown as a white lamp W. 70
- Entering signalled territory.*—After the train has passed through the section of unsignalled territory and again enters signalled territory the NS relay again assumes its deenergized position automatically by reason of the presence of both line and track 75
- circuit current which have a phase relation like that employed in signalled territory. 80
- Since it is possible for the first section of trackway in ordinary signalled territory to be in either caution or danger traffic conditions as well as clear, by reason of other trains, open sidings or the like, it might possibly happen that a train would enter signalled territory without causing deenergization of the NS relay. This is however not considered to 85
- materially endanger the train because the engineer will still be advised of his responsibility in running the train by the illumination of the white non-signal territory lamp W, and he will presumably take the proper 90
- precaution in response to such signal indications and if the section entered is a branch which is not provided with wayside signals he will run the train on train orders and 95
- proper observance of the track ahead. 100
- In equipping the entrance to non-signal territory with means for setting up non-signal territory control and indication, it is considered preferable to assure a clear trackway 105
- at least braking distance ahead, and for this reason the block K has been shown track circuited all the way through. It should be noted that the signal Z² has been shown dotted. This has been done because this signal 110
- may or may not be present depending on whether the non-signal territory section ahead is provided with wayside signals. If this section is provided with wayside signals this signal Z² will be controlled by traffic conditions in the two blocks in advance, in any 115
- suitable manner similar to the manner in which the signals Z and Z¹ are controlled. 120
- In the system of train control described, the well known means for controlling a three-position relay in a train control system of the continuous inductive type has thus been modified, so that, this relay assumes a deenergized position in a caution block as well as in an occupied block, provision being made 125
- to have a gradually decreasing speed limit 130

imposed to restrict the movement of a train in a caution block; advantage being taken of the reverse indicating position of the relay for setting up a distinctive control and 5 cab signal indication when the train enters territory not equipped for automatic train control purposes.

Further, the system proposed is so organized that line or simplex circuit equipment 10 may be advantageously used in regular train control territory. This for the reason that in two position continuous inductive train control systems where the regular track circuit is used also for train control purposes it is necessary to provide some means 15 for deenergizing the car-carried relay when a train moves through a caution block, because track circuit current must be present in a caution block and if the car-carried relay is controlled solely by track circuit current the main car relay would be deenergized. In the system shown caution conditions are manifested on the train by cutting current off of the line phase in a caution block. 20 It is of course inexpedient to cut off track current in a caution block because this would in effect change the condition of such block to that of an occupied block and cut off the current of the next block in the rear, and so 25 on; so that, some means of control is necessary in addition to that of the track circuit alone in two position control, which in the system shown consists of a controllable line 30 phase circuit. In the system shown the line phase car-carried equipment is used for both, effecting deenergization of the car relay in a caution block and setting up non-signal territory control by a suitable stick device which control continues effective until signal territory is reentered. 35

Having thus shown and described one specific embodiment of the present invention, it is desired to be understood that the specific disclosure has been made for the purpose of showing the nature of the invention and how it may be applied to, at least, one particular type of railway signal system rather than for the purpose of showing the scope of the invention, and that various 40 additions, changes or modifications may be made in adapting the invention to other types of systems without departing from the spirit or scope of the invention or the idea of means underlying the same.

55 What is desired to be secured by Letters Patent of the United States is:—

1. In an automatic train control system of the continuous inductive type, in combination, car-carried apparatus including a 60 three-position control relay for setting up clear and danger restrictions when it is energized in one direction and when it is de-energized respectively, means for giving a non-signal territory indication when said control relay is energized in the opposite

direction from said one direction, and trackway means for transmitting a control influence to said control relay under clear traffic conditions for causing said relay to indicate in said one direction, said trackway 70 means including means at the entrance to non-signal territory for energizing said relay to assume the reversed position.

2. In an automatic train control system of the continuous inductive type, in combination, a control relay adapted to be energized by alternating current derived from two trackway circuits to cause it to indicate in the normal direction when the trackway currents have a normal phase relation, to indicate in the reverse direction when the trackway currents have a reverse phase relation and to assume a deenergized position when either or both of these trackway currents discontinue flowing, means for picking up a non-signal territory relay when said control relay is energized in the reverse direction and for giving a clear traffic indication when said relay is energized in the normal direction, and trackway means for permitting the flow of trackway currents having a normal phase relation when traffic conditions ahead are clear in signalled territory and permitting a flow of current in similar trackway circuits having a reversed 85 phase relation at the entrance to non-signal territory.

3. In automatic train control systems of the continuous inductive type, the combination with a non-signal territory relay on the 100 vehicle of the stick type, of means including track-way means located only at the entrance to non-signal territory for automatically picking up said relay by currents flowing in two circuits along the trackway, said circuits 105 at the entrance to such unsignaled territory having a predetermined phase relation and for knocking-down said relay when similar trackway currents are encountered of which one of these currents is reversed.

4. In an automatic train control system of the continuous inductive type, in combination, a non-signal territory relay of the stick type positioned on the vehicle, and means for operating said relay including a section of trackway at the entrance end of the non-train control territory provided with a loop circuit, and a simplex circuit, each energized by alternating current, the currents in said two circuits having a relative instantaneous phase relation different from that which exists in any other part of the trackway.

5. In an automatic train control system of the continuous inductive type, in combination, circuits comprising the two track rails in multiple and energized by currents having certain instantaneous phase relations to other currents in said track rails, a non-signal territory relay of the stick type on the vehicle, and means partly on the vehicle and partly along 125 130

the trackway for picking up said relay including a circuit located only at the entrance to non-signal territory comprising the two track rails in multiple energized by a current 5 different, in instantaneous phase relation to other current in said two track rails, from that which occurs in any other part of the trackway.

6. In an automatic train control system of 10 the speed control type, in combination, a brake control device on the vehicle superimposed upon the usual air brake system, which if actuated causes an automatic application of the brakes, an actual speed device driven from 15 the wheels of the vehicle, a permissive speed device which if initiated from normal, sets up decreasing permissive speed limits in accordance with the progress of the vehicle along the trackway, means for actuating said 20 brake control device if the actual speed exceeds the permissive speed, a non-signal territory relay of the stick type, and an influence communicating means, of the type transmitting inductive influences continuous in character 25 to the vehicle, and located partly along the trackway and partly on the vehicle and including two trackway circuits having currents flowing therein having a normal phase relation in clear territory, a reverse phase relation at the entrance to non-signal territory 30 and having one or the other currents absent in caution and danger territory.

7. In an automatic train control system of the type in which a railway is equipped with 35 a three-position alternating current relay which assumes a normal, a reverse or a deenergized position in accordance with the presence of two trackway currents having a normal or a reverse phase relation respectively or in which one or both of these currents are absent, means for setting up clear traffic conditions on the vehicle when the relay assumes the normal energized position and setting up danger traffic conditions when 40 the relay assumes the deenergized position, said last mentioned means being ineffective to set up said danger traffic conditions if the relay assumes the reverse energized position before assuming the deenergized position under 45 which latter condition a non-signal territory indication is set up.

8. In an automatic train control system of a type in which a railway vehicle is equipped with a three-position alternating 55 current relay which assumes a normal, a reverse or a deenergized position in accordance with the presence of two trackway currents having a normal phase relation or a reverse phase relation respectively, or in which one or both of these currents are absent, means for setting up clear traffic conditions on the vehicle when the relay assumes the normal energized position and setting up danger traffic conditions when the relay assumes the 60 deenergized position, said last mentioned

means being ineffective to set up said danger traffic conditions if the relay assumes the reverse energized position before assuming the deenergized position under which latter condition a non-signal territory indication is set 70 up, said means including means for discontinuing the non-signal territory indication effective when said relay again assumes the normal energized position.

9. Trackway apparatus for automatic train 75 control systems comprising equipment in train control territory including a loop circuit comprising the two rails in series so that there are currents flowing in opposite directions along the track in said rails, and a simplex circuit comprising the two track rails in multiple which simplex circuit is energized only with current having a normal phase relation with respect to the loop circuit current, and equipment at the entrance to non-signal 80 territory comprising a similar loop circuit and a similar simplex circuit in which only currents flow having a reverse relative phase relation.

10. Trackway apparatus for automatic 90 train control systems comprising, signalled territory equipment including two trackway circuits adapted to transmit control influences to the vehicle one of which consists of the usual track circuit, said circuits having only 95 currents flowing therein having a normal phase relation with respect to each other and similar trackway circuits located only at the entrance to non-signal territory having currents flowing therein which have a reverse 100 phase relation from that of the currents in signalled territory.

11. An automatic train control system comprising, a brake control device, a permissive speed device, an actual speed device, means 105 for actuating said brake control device if the actual speed exceeds the permissive speed, a three-condition relay for controlling said permissive speed device to set up a lower permissive speed limit if said relay is de-energized, 110 trackway apparatus in train control territory for causing said relay to assume one energized condition when traffic conditions in advance are clear, similar trackway apparatus located only at the entrance to non-train control territory for causing said relay to assume a condition reverse from said one condition, and a non-signal territory relay caused to assume its energized position only if said three condition relay is energized to the reverse 115 condition, said non-signal territory relay if energized permitting said permissive speed device to remain in its condition of setting up a maximum permissive speed even though said three condition relay be de-energized. 120

12. In a train control system of the continuous inductive type in which the train is permitted to proceed in response to the flow of current flowing in the track rails, in combination, a main relay energized in response 130

to the flow of current flowing down one track rail through the axles of the train and back through the other rail and which relay if de-energized restricts the movement of the train, 5 a non-signal territory relay which if energized removes the restriction in the movement of the train imposed by said main relay, and means for causing said non-signal relay to assume its energized position while the train 10 is running in non-train-control territory including trackway means located only at the entrance to non-train-control territory for causing current to flow down one rail and back through the other and current flowing 15 down the two rails in multiple which last two mentioned currents have a predetermined phase relation different from what exists in other parts of the trackway.

13. A train control system of the continuous inductive type comprising, a trackway means for causing loop circuit current to flow down one rail through the axles of the train and back through the other rail and for causing simplex current to flow down the two 25 track rails in multiple, a three position relay carried on the train which assumes one energized position in response to such loop and simplex currents in train control territory under clear traffic conditions and assumes its 30 opposite energized position only upon entering non-train-control territory due to the phase relation between such loop and simplex currents in train control territory and at the entrance to non-train-control territory respectively, means for restricting the progress 35 of the train upon de-energization of said relay, and non-train-control territory means rendered active if said relay assumes said opposite energized position and then its deenergized position which means if active prevents 40 such restriction in the progress of the train.

14. An automatic train control system of the continuous inductive two position type comprising, means partly on the vehicle and 45 partly along the track in train control territory having the usual loop or track circuit current flowing down one rail and back through the other for restricting the progress 50 of the train in response to the absence of such loop circuit current, a non-train-control territory relay on the vehicle, and means for rendering said non-train-control territory

relay active including means for conducting currents having a predetermined phase relation down one rail and back through the other 55 and down the two track rails in multiple respectively, such predetermined phase relation existing only at the entrance to non-train-control territory.

15. An automatic train control system of 60 the continuous inductive two position type comprising, means partly on the vehicle and partly along the track in train control territory having the usual loop or track circuit current flowing down one rail and back 65 through the other for restricting the progress of the train in response to the absence of such loop circuit current, a non-train-control territory relay on the vehicle, means for rendering said non-train-control territory relay active 70 including means for conducting currents having a predetermined phase relation down one rail and back through the other and down the two track rails in multiple respectively, such predetermined phase relation existing 75 only at the entrance to non-train-control territory, and means for giving a distinctive signal indication on the train when said non-signal territory relay is energized.

16. In a train control system of the continuous inductive type in which the train is permitted to proceed in response to the flow of current flowing in the track rails, the combination of a main relay energized in response to the flow of current flowing down one track 85 rail through the axles of the train and back through the other rail and which relay if de-energized restricts the movement of the train, a non-train-control territory relay which if energized removes the restriction in the movement 90 of the train imposed by said main relay, and means for automatically causing said non-train-control relay to assume its energized position while the train is running in non-train-control territory including trackway 95 means located only at the entrance to non-train-control territory for causing current to flow down one rail and back through the other and current flowing down the two rails in multiple which last two mentioned 100 currents have a predetermined phase relation.

In testimony whereof I affix my signature.

WINTHROP K. HOWE.
